UNITED STATES PATENT OFFICE.

ANDREW PORTER STEUART, OF WESTPORT, AND HARRY MUSSINA WELLIVER, OF LOCK HAVEN, PENNSYLVANIA; SAID WELLIVER ASSIGNOR TO SAID STEUART.

CARPET-STRETCHER.

SPECIFICATION forming part of Letters Patent No. 375,019, dated December 20, 1887.

Application filed October 24, 1885. Serial No. 180,863. (No model.)

To all whom it may concern:

Be it known that we, ANDREW PORTER STEUART and HARRY MUSSINA WELLIVER, citizens of the United States, residing at Westport and 5 Lock Haven, respectively, in the county of Clinton and State of Pennsylvania, have invented certain new and useful Improvements in Carpet-Stretchers, of which the following is a specification.

Our invention relates to improvements in carpet-stretchers; and it consists in certain novel features, hereinafter described and claimed.

In the accompanying drawings, Figure 1 is 15 a perspective view of our improved carpet-stretcher in operative position, and Fig. 2 is a bottom plan view of the device, showing the several parts folded for storage and transportation. Fig. 3 is a side elevation of the same.

Referring to the drawings by letter, A designates the main bar or lever, of any suitable material and of any desired dimensions. At 20 one end of this lever A we form the handle B, and at the opposite end we pivotally secure to the under side of the same a metal plate, C, having its end bent, as shown, and provided with the teeth D along its edges. The plate thus constructed forms a claw, which engages in the carpet when the device is 25 being operated. The edges of the plate are not bent toward each other, but one edge is bent outward and the other edge is bent inward in a plane very nearly parallel thereto, so that as the said claw is forced forward over 30 the carpet it will engage therein and stretch the same, but as it is drawn backward over the carpet it will pass readily thereover without engaging therein.

E designates a fulcrum-bar, which is pivoted at one end to the under side of the main bar or lever, about the center of the same, and provided at its free end with the downwardly-turned point F.

G designates a claw similar to the claw C, pivoted to the under side of the main bar or lever, near the handle of the same.

In operation the fulcrum-bar is turned out from the main bar or lever, as clearly shown in Fig. 1, and the point F is driven into the 45 floor. The claw C is then made to engage in the carpet, and the handle B is then pushed in a direction contrary to the direction in

which the carpet is to be stretched. This action causes the claw C to draw on the carpet, as will be readily understood. When the 55 carpet has been sufficiently stretched, the claw G is made to engage in the carpet and hold it in its stretched position while being tacked or otherwise secured to the floor. These several parts being pivoted to the main lever, the pull 60 on the carpet will be in a straight line, for as the lever is pushed or pulled back the claw will turn on its pivot, so as to always pull on the carpet in a straight line. When the device is not in use, the several parts are turned 65 into the position shown in Fig. 2, lying entirely between the edges of the main bar, so as to take up the least possible room and facilitate packing for transportation and also allow the device to be laid aside in a very small 70 space.

From the foregoing description it will be seen that we have provided a very simple device, which can be readily operated by any person, however unskilled.

Having thus described our invention, what we claim, and desire to secure by Letters Patent, is--

1. A carpet-stretcher comprising a main bar, a fulcrum-bar secured thereto, and the 80 claws pivoted to the main bar and having their serrated edges bent so as to engage the carpet when the main bar is turned in one direction and slip over the same when it is turned in the opposite direction, substantially 85 as specified.

2. A carpet-stretcher comprising a main bar or lever, a fulcrum-bar pivoted thereto about its center, and claws pivoted to the under side of the same near its opposite ends, 90 substantially as set forth.

3. A carpet-stretcher comprising the main bar, the fulcrum-bar pivoted thereto, and the claws pivoted thereto near its opposite ends, the said claws consisting of metal plates having their ends bent in substantially parallel 95 planes and provided with teeth along their edges, substantially as described.

ANDREW PORTER STEUART.
HARRY MUSSINA WELLIVER.
